UNITED STATES PATENT OFFICE

FREDERICK W. HECKERT, OF NEAR DAYTON, OHIO

FIRE EXTINGUISHING AND BURGLARY PREVENTING MEANS

Application filed October 1, 1928. Serial No. 309,604.

This invention relates to new and useful improvements in fire extinguishing and burglary preventing means.

It is one of the principal objects of my invention to provide a simple, compact and efficient fire extinguishing unit which may be automatically operated from the wall bracket that supports it, or which may be easily withdrawn from that bracket for hand operation.

It is another object of my invention to provide a hand-operated fire extinguisher that may be converted into an automatic one by the addition of a fusible link or magnetically controlled operating device. The latter is so constructed that it may be taken from stock for easy attachment to the wall plate supporting the extinguisher. Thus the hand-operated fire extinguisher may be first ordered, and later, the device for automatically operating it if desired.

It is another object of the invention to provide for inclusion in the automatically operated unit, a suitable electric fire alarm for actuation by the same means, such as a hammer lever, that releases an expelling fluid from a conventional gas container and simultaneously actuates the fluid discharge valve.

It is another object of my invention to provide a discharge valve body that may be easily removed from the head of the fluid-containing cylinder to render the valve and associated parts accessible for repair or replacement.

My device may also be used as an efficient burglar alarm by suspending it adjacent to or on a door or window, so that when the latter is opened, contacts will be engaged to close an electric circuit through a heater coil located adjacent a fusible link such as the solder connection. The latter will then be melted to set in operation a loud alarm and at the same time to operate the discharge to release a distracting chemical such as tear gas.

Other important and incidental objects will be brought out in the following specification and particularly set forth in the subjoined claims.

In the accompanying drawings illustrating my invention, Figure 1 is a front view of my device. Figure 2 is a side view of the same, showing the wall bracket for supporting it. Figure 3 is a top view of the device, showing the electric contacts. Figure 4 is a top view of said device taken below the releasing mechanism. Figure 5 is a perspective view of the electrical contacts, showing the associated electrical circuits. And Figure 6 is a longitudinal sectional view taken through the discharge valve body, showing the discharge valve and associated parts.

Referring to the accompanying drawings for a detailed description of the forms of embodiment of my invention disclosed therein, the numeral 1 designates a wall plate formed with an end flange 2 and a right-angled retaining lug 3 secured by screws 4 to the front portion of said plate. Secured to the wall plate 1 between its rear flange portion 2 and retaining lug 3 are spring clips 5 properly spaced to receive between them a liquid or gas container such as the cylinder 6. The plate 1 is adapted to be secured to a wall to support the liquid or gas container for automatic use, or for easy withdrawal from the spring clips 5 for hand use if desired.

The cylinder 6 is closed at its front end by a removable head 7 from the middle portion of which there projects forwardly a boss 8. Mounted within the latter is a piercing pin 9 for a small receptacle such as a cartridge 10. The latter contains a gas which when released, acts as an expelling agent for a fire extinguishing fluid, or a burglar incapacitating chemical, within the main body of the cylinder.

The expelled fluid or gas flows from the rear end of the cylinder through a pick-up tube 11 connected at its front end to a discharge valve body 12.

Referring to Figures 1 and 6, there is formed in the cylinder head 7 a hole having a threaded periphery which receives the valve body 12. The latter is formed with a standard taper pipe thread that makes possible a tight joint without the use of gaskets.

At its middle portion the valve body 12 is formed with a hex portion 13 having a radial

discharge orifice 13^a. It is easily possible, by turning the threaded valve body 12 with a wrench applied to its hex portion 13, to place the discharge orifice 13^a in proper register with the front end of the extinguisher.

Referring to Figure 6, the numeral 14 designates a valve having a stem 14^a that is threaded at its outer end to receive a spring retaining nut 14^b. Between this nut and a guide washer 15 anchored against an annular shoulder or flange 15^a formed within the valve body 12, is a helical spring 16 which surrounds the valve stem 14^a. This spring is under compression to hold the valve 14 tightly against a valve seat such as the vellumoid gasket 17 on the other side of the shoulder 15^a. On the outer end of the valve body is a jamb nut 18 and a packing nut 18^a. The latter is formed with a hole through which the nut 14^b projects.

Between the jamb nut 18 and the hex portion 13 of the valve body 12, a flanged supporting piece 19 is received. The latter is formed at its upper end with a bearing 20 for a removable pin 21.

Straddling the bearing 20 for pivotal support by the outer ends of the pin 21, are two arms 22, 22 on a lever 23. The latter has a wide circular, downwardly projecting middle portion that is formed with a central hole 24 to clear the boss 8 of the cylinder 6, and terminates below it in a projection 25 for engagement by a nose piece 26 on a hammer lever 27 hereinafter to be described. (See Figures 1, 2 and 4.)

The projections 25 also serve as a finger press when the extinguisher is hand operated.

Upon its inward movement the lever 23 is adapted to engage the nut 14^b on the stem of the valve 14 to force the latter from its seat 17, whereupon the liquid within the cylinder 6 is free to pass out of the discharge orifice 13^a in the hex portion 13 of the valve body 12.

The valve 14 and its associated parts may be easily removed from the cylinder 6 for cleaning or repair by unscrewing the valve body 12 from the cylinder head.

Formed in the middle portion of the hammer lever 27 is a threaded hole which receives a stud 28 having a reduced inner end that is adapted to engage the piercing pin 9 to puncture the cartridge 10. The lever 23 will be engaged at the same time by the nose piece 26 in the lower end of the hammer lever 27, to engage the nut 14^b on the stem of the valve 14 which, being then moved from its seat, will permit the discharge of the fluid expelled from the cylinder by the gas such as carbon dioxide released from the cartridge 10. (See dotted lines in Figure 2.)

The hammer lever 27 suspends from a pin 28^a secured between supports 29, 29 formed with feet 30 attached to the wall plate 1. Collars 31, 31 center the lever 27 on the pin

28^a. (See Figures 2 and 3.) After the extinguisher is received and it is desired to make it automatic in its operation, the hammer lever actuating device may be ordered and attached to the wall plate 1 by the feet 30. 70

The hammer lever 27 is normally held in a horizontal position by the following means. Referring to Figure 2, there is secured to a stud 32 at the front end of the wall plate 1, a strap 33 which has a solder connection 34 75 with a strap 35. The latter is connected by a screw 36 to the end of the hammer lever 27.

The strap 35 is secured at its outer end by a screw 37, within the bifurcated end of a rod 38. The other end of this rod is formed 80 with a hole to receive one hook end 39 of a coiled wire 40.

The other hook end 41 of the coiled wire 40 is received by a hole formed in one end of a rod 42. This rod 42 passes through a 85 hole in the flange portion 2 of the wall plate 1, the other end of the said rod 42 being threaded to receive a wing nut 43.

The above described fusible link construction may also be easily attached to the wall 90 plate 1.

After the solder 34 is melted, due to the increase in temperature from a fire, the connection between the straps 33 and 35 is broken, thus leaving the hammer arm 27 free 95 to be pulled toward the cylinder 6 by the contracting force of the coil 40 to engage the piercing pin 9 and valve stem nut 14^b.

The outward movement of the hammer lever 27 is limited by a screw 27^a secured to 100 the boss 8. When it is desired to remove the valve body 12, the screw 27^a may be withdrawn, the screw 36 removed and the pivot pin 21 taken out, whereupon the hammer lever 27 may be taken off. A wrench may 105 then be applied to the hex portion 13 of the valve body 12 to unscrew it from the cylinder head.

The release of the hammer lever from its 110 normal position effects the closing of an electric circuit which sets in operation a fire alarm simultaneous with the piercing of the cartridge 10 and the opening of the fluid discharge valve 14.

The arrangement of this alarm in relation 115 to the device is as follows. A support such as the T-shaped bakelite base 44 is secured to the hammer lever 27 below the stud 28 with two threaded studs 45 and 46. Within a hole 120 in the upper portion of the base is seated a binding post 47 with its threaded end extending outward to receive a nut 48 and a knurled nut 49. A copper contact 50 is secured to said binding post 47 below the nut 48. This contact 50 is shaped over the edge 125 of the base 44 and is adapted to engage a contact 51 when the hammer lever 27 swings inwardly from its normal position. The contact 51 is held in position against the leg 29 by a binding post 52 passing through a hole 130

in one end of the said contact 51. Said binding post has its threaded end extending outwardly to receive a nut 55. An electrical connection between this binding post and the leg 29 is prevented by fibre washers 53 and 54. (See Figures 1, 3 and 5.)

An electric circuit through the burglar alarm is defined as follows. (See Figure 5.) A wire 56 leads from the binding post 47 to one pole of a battery 57. The circuit is continued from the opposite pole of said battery 57 through a wire 58 to an electrical alarm 59, then through the electromagnets of said alarm 59, through a wire 60 to the binding post 52 and contact 51. Thus when the lever arm 27 is pulled inwardly by the contracting force of the coil 40, the contact 50 will engage the contact 51 to close said circuit to set in operation the alarm 59.

A second and independent circuit is provided to energize a heating coil 61. (See Figure 5.) From one pole of a battery 62, or other source of electrical energy, there is a wire connection 63 to a binding post 64 which rests in a hole in one arm of the T-shaped bakelite base 44. This post receives over its threaded end, which extends outwardly, a copper clip 65 below a lock nut 65^a and a knurled nut 65^b. To the outer end of the clip 65, which is shaped over the edge of the bakelite base 44, is connected one end of the heater coil 61. This coil is mounted on a porcelain spool 66 which is secured to a screw 66^a attached to the base 44. The other end of the coil 61 is connected to a clip 67 which is constructed after the fashion of the clip 65, and secured to the binding post 68 on the base 44 below a lock nut 69 and a knurled nut 70. Thus the construction of this binding post 69 and its connections are the same as that of binding post 64 and its connections.

A wire 71 connects the binding post 68 with the contact 72. The contact 73 is connected to the opposite pole of said battery 62 by a wire 74. Contacts 72 and 73 are adapted to engage so as to close the circuit. (See Figures 1, 3 and 5.)

The purpose of this circuit is to provide a means by which the device can be used as a burglar alarm instead of a fire extinguisher. Thus the contacts 72 and 73 can be secured, one to a door or window and the other to the casing of the door or window, so that they will engage when the door or window is opened. Their engagement will close the circuit through the battery 62 and heater coil 61. The latter will generate sufficient heat after the circuit is closed to melt the solder connection 34 which is located adjacent to the said coil 61. (See Figures 2, 3 and 5.)

As soon as the solder 34 is melted, the connection between straps 33 and 35 is broken and the hammer lever will swing inwardly toward the cylinder 6 by the force exerted upon it due to the contracting of the coil 40.

Three operations will be set up independently with the inward movement of the hammer lever 27. The contact 50 will engage the contact 51, thus closing the circuit through the battery 57 and setting in operation the alarm 59.

The reduced inner end of the stud 28 will engage the piercing pin 9 and puncture the cartridge 10, thus releasing the expelling gas. At the same time the nose piece 26 on the hammer lever 27 on its inward swing will engage the projection 25 of the lever 23. The latter being adapted to engage the nut 14^b on the stem of the valve 14, will open the valve, whereupon the fluid in the cylinder 6 will be free to pass out of the discharge hole 13^a in the hex portion 13 of the valve body 12.

If it is desired to use the device for burglary prevention, the cylinder 6 can be filled with a distracting chemical such as tear gas, which will be expelled through the pick up tube in the cylinder 6 and valve 14, by the gas released from the cartridge 10. With the simultaneous operation of the alarm, this device provides an efficient burglary preventive means.

I do not desire to be limited to the details of construction and arrangement herein shown and described, and any changes or modifications may be made therein within the scope of the subjoined claims.

Having described my invention, I claim:

1. In a device of the type described, a cylinder formed with two openings in its head portion, a gas-container within said cylinder adjacent one opening therein, a valve body in the other opening in said head portion, a valve within said body, stem means on said valve projecting beyond said head portion, a lever pivotally mounted on said valve body for actuation of said stem means, a puncture pin for opening the gas container also projecting beyond said head portion, a hammer lever for engagement with said first mentioned lever and puncture pin, resilient means for drawing the hammer lever into engagement with the puncture pin and the valve stem lever to force them inwardly, and a connection adapted to be broken by heat for holding said hammer lever out of engagement with said valve stem lever and puncture pin.

2. In a device of the type described, a cylinder formed with two openings in its head portion, a gas-container within said cylinder adjacent one opening therein, a valve body in the other opening in said head portion, a valve within said body, stem means on said valve projecting beyond said head portion, a lever pivotally mounted on said valve body for actuation of said stem means, a puncture pin for opening the gas-container, also projecting beyond said head portion, a hammer lever for engagement with said first mentioned lever and puncture pin, a spring for

drawing said hammer lever into engagement with the valve stem lever and puncture pin to force them inwardly, and a fusible connection for holding said hammer lever away from the valve stem lever and puncture pin.

3. In a device of the type described, a wall plate, a cylinder having a discharge opening, clips on said plate for supporting said cylinder, a gas-container within said cylinder, a pin projecting beyond the head of said cylinder for puncturing said gas container to release the gas therein, a hammer lever for engaging said puncture pin, a support on said wall plate to which said lever is pivoted, spring means on said wall plate for drawing said lever into puncturing engagement with the puncture pin, and a solder connection on the wall plate for holding the hammer lever out of engagement with said puncture pin for the purpose specified.

4. A fire extinguisher comprising a fluid containing cylinder having a discharge opening in its head, a wall bracket removably supporting said cylinder, a valve controlling said discharge opening, a hand press for actuating said valve, and a fusible link and a valve operating device attached to said wall bracket adjacent said head for automatically actuating said valve on fusing of said link.

5. A fire extinguisher comprising a fluid containing cylinder having a discharge opening in its head, a wall bracket for removably supporting said cylinder, a valve controlling said discharge opening, a gas container within the head portion of the cylinder, means for puncturing said container to release gas therefrom to expel the fire extinguishing fluid through the discharge opening, a hand press for actuating said valve and puncturing means, and a fusible link device and means attached to said wall bracket adjacent the head of the cylinder to automatically actuate the hand press to operate the gas-container puncturing means and the valve on fusing of said link.

6. In a device of the type described, a fluid containing cylinder formed with a discharge opening, valve means for controlling the passage of said fluid through the opening, a hammer lever adjacent the head of said cylinder to engage said valve means, an alarm, an electric circuit including said alarm, and contact means adapted to be actuated by said lever to close said circuit to operate the alarm at the time the valve means are operated.

7. In a device of the type described, a cylinder formed with two openings, a gas-container within said cylinder, means for puncturing said gas container, a discharge opening, valve means for controlling discharge of cylinder contents through said valve opening, a hammer lever adjacent the head of said cylinder for operation of said valve means

and puncturing means, an alarm, an electric circuit including said alarm, and contact means adapted to be actuated by said circuit to operate said alarm at the time the valve means and puncturing means are operated.

8. In a device of the type described, a cylinder formed with two openings, a gas-container within said cylinder adjacent one opening therein, a valve body in the other opening, a valve within said body, stem means on said valve projecting beyond said valve body, a member for actuating said stem means, a puncture pin for opening the gas-container, and a hammer for the simultaneous operation of said valve stem actuating member and the puncture pin.

9. In a device of the type described, a cylinder formed with two openings, a gas container within said cylinder adjacent one opening therein, a valve body in the other opening, a valve within said body, a stem on said valve projecting beyond said valve body, means for actuating said valve stem, a puncture pin for opening the gas container, a hammer for the simultaneous operation of said valve stem actuating means and the puncture pin, and a fusible connection for holding said hammer away from the valve stem actuating means and the puncture pin.

In witness whereof I have hereunto set my hand this 20th day of September, 1928.

FREDERICK W. HECKERT.
